US00D843386S

(12) **United States Design Patent** (10) **Patent No.:** **US D843,386 S**
Shewman (45) **Date of Patent:** **** Mar. 19, 2019**

(54) **DISPLAY SCREEN WITH GRAPHICAL USER INTERFACE FOR ASPECT RATIO SELECTION**

(71) Applicant: **PRYSM, INC.**, San Jose, CA (US)

(72) Inventor: **William M. Shewman**, Noblesville, IN (US)

(73) Assignee: **PRYSM, INC.**, San Jose, CA (US)

(**) Term: **15 Years**

(21) Appl. No.: **29/617,898**

(22) Filed: **Sep. 15, 2017**

Related U.S. Application Data

(62) Division of application No. 29/620,230, filed on Feb. 8, 2016, now Pat. No. Des. 797,768.

(57) **CLAIM**

The ornamental design for a display screen with graphical user interface for aspect ratio selection, as shown and described.

DESCRIPTION

The FIGURE is a front view of a display screen with graphical user interface showing the new design.

The outer broken lines in the FIGURE show a display screen or a portion thereof that forms no part of the claimed design. The inner broken lines in the FIGURE show portions of the graphical user interface that form no part of the claimed design.
